PLASTERER'S ANGLE PLANE

Hannibal P. Huffman, Seattle, Wash.

Application September 15, 1947; Serial No. 773,969

2. Claims. (Cl. 72—136)

1.

This invention relates to what is known in the art to which it applies as a "plasterer's angle plane," and has reference more particularly to a tool whereby the angles or corners of walls plastered with the first or brown coat may be planed down for the purpose of trueing up the angles and for removing from the surfaces any pieces of sand, plaster or trowel marks and ridges that would interfere with the application and smoothing up of a finish coat of plaster.

It is the principal object of my invention to provide an angle plane of an improved form, comprising a main frame member to which a handle is attached and in which a plurality of wall planing blades are mounted in an angular relationship both with respect to the handle and to each other and which in a planing action will simultaneously scrape or act on the plastered surface. Furthermore, it is an object of the invention to provide an angle plane equipped with a plurality of blades so that the work of planing down, or trueing up an angle or surface may be greatly speeded up and more effectively accomplished.

Still another object of my invention is to provide an angle plane wherein the blades are self-aligning, which will wear evenly and will retain their sharp corners. Furthermore, blades that are mounted in a frame in such manner that they may be readily removed for replacement when such is desired.

Still further objects of my invention reside in the details of construction of the various parts, in their combination and in the mode of use of the tool, as will hereinafter be fully described.

In accomplishing the above mentioned and other objects of the invention, I have provided the improved details of construction, the preferred forms of which are illustrated in the accompanying drawings, wherein—

Fig. 1 is a perspective view of a plasterer's angle plane embodied by the present invention.

Fig. 2 is a perspective view of the same, as shown in an inverted position.

Fig. 3 is a top or plan view of the plane.

Fig. 4 is a side view of the same.

Fig. 5 is a plan view of an end portion of the plane as seen from the under side, showing the angular direction of the blades as applied to the main frame and showing a slot as formed in the frame member for mounting one of the blades.

Fig. 6 is a cross section, taken on the line 6—6 in Fig. 4.

Fig. 7 is a face view of a planing blade designed for planing a cove surface.

Referring more in detail to the drawings—

The main frame structure of the present tool comprises a length of sheet metal tubing 10; this being hollow and open at its ends and in cross section being of the shape of an equilateral triangle. In a size now found to be quite satisfactory for most uses, the frame member 10 is approximately twelve inches long and measures about two inches across any of its side surfaces, but these dimensions may be varied.

Secured to the top side of the frame, this being one of the flat surfaces of the tube, is a handle. Preferably the handle is made from a single piece of sheet metal, with a portion thereof rolled to form a hollow or tubular hand hold portion 12. At the opposite ends of the hand hold portion, legs 13—13 are provided, and these are flanged at their ends for securing to the top wall of the frame member by welding, riveting or other suitable means of connection. As observed in Fig. 4, the handle is of substantial length and is symmetrically located on the frame.

Formed through the lower portion of the frame by cutting through its opposite side wall portions are angularly directed slots 20, one of which is well shown in Fig. 5 at the left hand end of the view. The slots are evenly spaced apart along the frame member, and alternate slots are inclined in opposite directions, each at an angle of about thirty degrees with respect to the longitudinal edge of the frame. Set within each of the slots is a planing or scraping blade 22, all blades being of the same size and shape and of rectangular form and formed from metal of a kind suitable for the intended use. In the present instance, I prefer to use sheet steel of about twenty-two gauge. All blades have their end and longitudinal edges cut straight and square, and the blades are of such length that their end edges will terminate close together and substantially in alignment, as will be understood by reference to Fig. 3. When seated in the slots 22 of the frame member, all blades will be supported with their scraping edges in the same planes.

It is to be pointed out that, as an additional advantage in the use of the present device, the end edges of the blades lie beyond the end and side limits of the frame member 10. This will be understood best by reference to Fig. 3, wherein it is noted that the ends of the blades extend substantially beyond the side edges of the frame member 10. Also, the ends of the blades that are mounted at the ends of the frame member extend beyond the planes of the end surfaces of the

frame. This insures that the frame will at no time interfere with a planing action. Furthermore, the blades extend sufficiently to the sides of the frame and handle that there is no danger of the user rubbing the wall with his hand when grasping the handle member.

In order that the blades may be held securely in place, each is provided centrally with a hole or opening 25, and when the blades are seated in proper position in the frame slots, these holes will be in alignment and in position to receive a locking rod 28. The arrangement is such that the locking rod will be seated within the lower angle of the tubular frame member, as well shown in Fig. 6 and will hold all blades firmly seated in their mounting slots.

It is to be explained further that the arrangement of parts is such that the blades 22 may be inverted or reversed in position and secured by the rod 28 applied through the same holes in either position of use. Should it be desired to change the blades, it is required only that the rod be withdrawn. This releases all of the blades, and they may be readily lifted out of their retaining slots.

It is also anticipated that blades of different shape than those shown in Fig. 6 might be employed, for example, a blade as at 30 in Fig. 7 formed with a curved scraping edge 31 adapted to fit within the curvature of a cove molding or ceiling. Blades of other shapes also might be employed to meet special conditions.

Angle planes so made are long wearing, easy to handle, light in weight and especially effective in use. The angles of the blades will wear sharp and square regardless of the extent of use and will be self-aligning in that should one extend slightly beyond another at the beginning of use, it will readily wear or adjust itself so that its edges will be perfectly aligned with the edges of others of the plane.

Devices of this character may be made in different sizes and in different proportions than herein illustrated, and also may be equipped with varying numbers of blades. Furthermore, the frame member 10 might be made of wood, plastic, or of cast metal, such as for example, aluminum. Therefore, it is not desired that the following claims shall be restricted to the details of construction herein shown but that they shall be

given an interpretation that is commensurate with the scope of the invention which has been disclosed.

While I have illustrated and described the frame member as being a metal tube of triangular cross-sectional shape, it is not desired that the invention should be limited thereto, since it is anticipated that this member might be round, square or of other appropriate shape, and furthermore, it might be made of wood or plastic.

Having thus described my invention, what I claim as new therein, and desire to secure by Letters Patent, is:

1. An angle plane of the character described comprising a rigid, centrally located longitudinal frame member of tubular form, a handle fixed thereto at its outside of the top wall, and there being slots cut through the frame member across its inside, alternately inclined in opposite directions, scraping blades disposed edgewise in said slots, and extending substantially to opposite sides of the frame member, each being made of resilient metal and having a longitudinal scraping edge and scraping edges at opposite ends, said longitudinal edges all being in the same plane, and scraping edges at opposite ends being in the same planes; each of said blades having a hole therethrough, and a blade locking rod seated in said tube against the bottom wall and extended through said holes of the blades to secure them seated in their mounting slots.

2. A device as in claim 1 wherein the tube is of triangular form in cross section, and said slots are cut through converging walls thereof, and said blades engage at their top edges against the base edges of the slots and said locking rod is seated in the angle formed by the converging walls.

HANNIBAL P. HUFFMAN.
